Patented Dec. 3, 1918.

UNITED STATES PATENT OFFICE.

AUGUST H. DEIKE, OF TAKOMA PARK, MARYLAND.

WATER-CLOSET.

1,286,249.

Specification of Letters Patent.

Patented Dec. 3, 1918.

Application filed April 24, 1917. Serial No. 164,241.

To all whom it may concern:

Be it known that I, AUGUST H. DEIKE, a citizen of the United States, residing at Takoma Park, Montgomery county, State of Maryland, have invented certain new and useful Improvements in Water-Closets, of which the following is a specification.

This invention relates to water closets and more particularly to automatically operating ventilated closets.

The objects of the invention are to provide a closet of this type in which the flow of water to the flushing tank is controlled by the seat, either depression of the seat or raising the same opening the valve which permits the flow of water; to provide a pipe connecting the tank and bowl which shall act both as a flushing and ventilating pipe; to provide a flushing valve which shall also act as an overflow pipe and a ventilating means; to provide an air-tight flushing tank and means for exhausting the air therefrom thereby producing a circulation of air and gases from the bowl to the tank; to provide an exceedingly simple and reliable means for operating the flushing valve; to provide means whereby the flushing valve is closed by the flow of water to the tank; to provide a novel and exceedingly simple means for exhausting the air from the tank, which is actuated by the flow of water to the tank; and generally to improve constructions of this type so that a minimum number of simple parts are used, thereby giving a structure which is dependable and operates with a minimum amount of attention.

Other objects will be apparent from the description taken in connection with the drawings in which:

40 Figure 1 is a plan view of the apparatus, the top of the tank being removed to show the parts located therein;

Fig. 2 is a side elevation, the side of the tank being removed and the seat being shown in depressed position;

Fig. 3 is a front elevation, with the front of the tank removed and showing the seat in depressed position.

The apparatus consists of a bowl 10 which 50 may be of the usual type and a flushing tank 11 located above the bowl and connected thereto by a short flushing pipe 12, which leads from the bottom of the tank to the side of the bowl near the top thereof.

55 The bowl is provided with the usual seat 13

and when depressed is adapted to operate the plunger 14 to open the valve 15, which, through the pipe 16, is connected with a water supply. The outlet of the valve 15 is connected by means of a conduit 17 with the tank so that water may be supplied thereto. The normal position of the seat 13 is shown in dotted lines in Figs. 2 and 3. It will thus be apparent that when the seat is depressed water will be supplied to the flushing tank. Means is also provided so that when the seat 13 is raised to a substantially vertical position, the valve 15 will also be opened. For this purpose, one of the hinge members 18 of the seat is formed with a 60 crank 19 which pivotally engages with a link 20, the other end of which is connected by means of a pin 21 and slot 22 with a lever 23 pivoted as at 24 on a bracket 25 which may be carried by the conduit 17. 65 The end of the lever 23 opposite the pin 21 is formed with a yoke 26 and the arms of this yoke are each formed with slots 27 which are adapted to receive pins 28 carried by the plunger 14. A spring 29 which 70 may be interposed between the pin 21 and the conduit 17 acts to raise the plunger 14 and hold the valve 15 closed. It will be apparent that when the seat 13 is raised to a substantially vertical position, through 75 the crank 19 and link 20, the lever 23 will be rocked to thereby depress the plunger 14 and open the valve 15, thus permitting water 80 to flow to the tank.

All of the apparatus for ventilating the 90 bowl and actuating the flushing valve is located within the tank, which may be of any desired construction, the only requirement being that it shall be substantially air-tight. As clearly shown in the drawings; the conduit 17 extends through the bottom of the tank and through a bracket fitting 30 which is held rigid in any desired manner. This bracket 30 has a short section 31 of the conduit extending vertically therefrom and substantially parallel therewith a standard which consists of a vertical member having a horizontally arranged arm 33 at the upper end thereof for a purpose presently to be described. 95 Arranged near the end and slightly below the said arm 33 is the discharge section 34 of the conduit, which may be provided with the spray nozzle 35 through which the water 100 is discharged. The discharge section 34 is 105 110

arranged at an angle to the section 31 of the conduit and these two sections may be connected by means of a section 36 which is yieldably secured to said sections 31 and 34. 5 For this purpose the connecting section may be a piece of flexible tubing, although any other suitable means may be used, the only requirement being that the said connecting section 36 be joined to the sections 31 and 34 10 so that the section 34 may be permitted to move under the force of reaction due to the flow of the water through the bend 37 in said connecting section. It is therefore obvious that this connecting section might 15 consist of a rigid tube having the bend 37 therein and connected at its ends with the sections 31 and 34 by universal joints. The discharge section 34 of the conduit is provided with a pair of oppositely extending pins or trunnions 38 and 39 each of 20 which is pivotally connected to a pair of links 40 and 41, which are arranged to form a toggle joint. For this purpose the links 40 at their upper ends are pivotally 25 carried by pins 42 secured to the arm 33 previously described. The links 41 extend downwardly from the trunnions 38 and 39 and at their lower ends are pivotally secured at 43 to a vertically arranged tubular 30 member 44 which constitutes the flushing valve. Thus the flushing valve 44 is of sufficient height so that it forms an over-flow pipe and at its lower end is adapted to seat against a fitting 45 in the bottom of the 35 tank to thereby close the opening to the flushing pipe 12 to thereby permit the tank to be filled with water to a height equal to the height of the member 44. The flushing valve is mounted for movement away 40 and toward the bottom of the tank by means of two parallel links, one arranged at the top of the valve and the other near the bottom thereof. As clearly shown in the drawings, the upper link consists of a yoke member 46, the two arms 47 and 48 of which are arranged on opposite sides of the valve 44, and the standard 32. The ends of these 45 arms are connected to the valve 44 by means of the pins 43 and near the base of the fork 50 are pivotally mounted on the standard 32 by means of the brackets 49. The arms 47 and 48 are slidably through the brackets 49 and are adapted to be secured in adjusted position by the set screws 50. The stem 51 55 of the yoke has a weight 52 slidably mounted thereon and adapted to be secured in any adjusted position by a set screw 53. The link at the lower end of the valve is arranged similar to the link just described, 60 except that it is not necessary to provide the same with a weight similar to the weight 52. As shown, this lower link has the side arms 54 which at one end are connected by means of pins 55 with the valve and at the 65 other end are pivotally connected to the

standard 32 by the brackets 56 through which the arms are slidable and adapted to be secured in adjusted position by the set screws 57. The arrangement of the parts just described is such that the weight 52 is 70 just sufficient to throw the toggle joints into the position indicated by the dotted lines and thereby raise the flushing valve 44 off its seat at the bottom of the tank. When water flows through the supply conduit the 75 force of reaction due to the deflection of the stream because of the bend 37 causes the discharge section 34 with its nozzle 35 to move toward the left as viewed in Fig. 3, thereby shifting the toggle joint from the 80 dotted line to the full line position and thus forcing the flushing valve to its seat and preventing the water from flowing through the flushing pipe 12 until the tank has been filled to a level with the top of the 85 flushing valve 44.

In order to ventilate the bowl as previously stated, a circulation of air and gases is maintained from the bowl through and out of the tank. For this purpose the tank is 90 made air-tight and the nozzle 35 of the discharge section of the conduit is mounted in spaced relation within a nipple 58 extending from the top of a hollow cylindrical member 59, the interior of which constitutes a separating chamber. The top of this cylindrical member is closed and the bottom edge is formed with a series of feet 60, thereby forming between the same a series of notches 61 to permit water to pass from the interior 95 of the member 59 into the tank. At the rear side and near the top, the member 59 is provided with an air discharge passage 62. In order to secure the cylindrical member 59 in position, a ring 63 may be arranged 100 around the same near the base thereof with one end extending through and secured to the rear wall of the tank. In the operation of this ventilating means the water discharged through the nozzle 35 exercises an 105 aspirating action, drawing air along with it through the nipple 58 and into the separating chamber, where the air passes out through the discharge opening 62 and the water falls to the bottom and passes through 110 the opening 61 to fill the tank. Of course, this aspirating action of what may be termed the gas or air ejector tends to exhaust the air from the tank and this reduction of pressure within the tank causes air and gases to 115 be drawn through the flushing pipe 12 and flushing valve 44 into the tank. Thus air and gases are continually withdrawn from the 120 bowl.

In the operation of the apparatus when 125 the seat 13 is either depressed or raised the valve 15 is opened, thereby permitting water to be supplied to the tank. This flow of the supply water causes the flushing valve to be closed and also operates the gas or air 130

5 ejector to ventilate the bowl. When the seat is permitted to assume its normal position the weight 52 raises the flushing valve 44, thereby permitting water to flow to the bowl to flush it out and as the movement of the seat to its normal position closes the water supply valve 15 the gas or air ejector no longer operates and the ventilating action therefore ceases.

10 Having thus described the invention, what is claimed and desired to be secured by Letters Patent is:

1. In a ventilating closet construction, a substantially air-tight tank having a gas outlet, a bowl, a single pipe connecting the tank and bowl, means for effecting a discharge of gas from said tank, and a flushing valve for said pipe formed with a passage therethrough forming an extension of the pipe, whereby the flushing valve also acts as an overflow and ventilating means.

2. In a ventilating water closet construction, a substantially air-tight tank, a bowl, a single pipe connecting the tank and bowl, means for effecting a discharge of gas from said tank, and a flushing valve for said pipe comprising a tubular member adapted to form an extension of said pipe and thereby also constitute an overflow and ventilating means.

3. In a ventilating water closet construction, the combination of a bowl, a flushing tank, a flushing pipe connecting said tank and bowl, a flushing valve, controlling said pipe, ventilating means for the closet operated by water supplied to the tank, means for closing said valve operated by the flow

of water to the tank, and means for controlling said flow.

4. In a ventilating water closet construction, 40 a substantially gas-tight flushing tank, a pipe connecting the tank and bowl, means for effecting a discharge of gases from said tank, and a flushing valve controlling said pipe formed with a passage for air and 45 gases.

5. In a ventilating water closet construction, 50 a substantially gas-tight flushing tank, means for supplying water to said tank, means for effecting a discharge of gases from the tank including a gas ejector arranged within the tank, and a conduit for air and gases connecting the tank and bowl.

6. In a ventilating water closet construction, 55 a substantially gas-tight flushing tank, means for supplying water to said tank, means for effecting a discharge of gases from the tank including a gas ejector arranged within the tank and operated by the flow of water to the tank, and a conduit for air and 60 gases connecting the tank and bowl.

7. The combination of a water closet bowl having a compressible seat, a flushing tank, a gas ejector, a flushing pipe connecting the tank and bowl and adapted to control the 65 flow of water to the bowl, a water supply connected to said ejector, a valve operated by the seat for governing the flow of water to the ejector, means whereby the flow of water to the ejector closes the flushing valve, 70 and means for opening said valve when the flow ceases.

In testimony whereof I affix my signature.
AUGUST H. DEIKE.
